METHOD OF AND APPARATUS FOR SEPARATING ORE OR METAL OF HIGH SPECIFIC GRAVITY

Application filed November 6, 1931, Serial No. 573,508, and in Germany November 7, 1930.

Our invention relates to improvements in the method of and apparatus for separating ore or metal of high specific gravity from earth or comminuted ore, and the object of 5 the improvements is to provide a method and an apparatus by means of which mineral or metal such as precious metal of high specific gravity is separated from ore or earth in which the heavy particles are contained in 10 a state of finest distribution. Another object of the improvements is to provide a method and an apparatus by means of which the said heavy particles are completely separated from the other particles, and by means of 15 which the heavy particles are obtained in separate deposits. Another object of the improvements is to provide a process in which the heavy particles are in contact only with the water or other liquid used for separating 20 the same, and in which they are not brought in contact with the air. Thereby a loss of heavy material is avoided which is caused by the said heavy material floating on the surface of the water when it is in a state of finest 25 subdivision, and when it is brought in contact with the air. Other objects of the improvements will appear from the following description.

For the purpose of explaining the invention 30 an apparatus suitable for putting the method into effect has been illustrated in a diagrammatic way in the single figure of the accompanying drawing, in which the said apparatus is shown in sectional elevation.

35 In the construction shown in the drawing the apparatus is particularly suitable for use in laboratories for ascertaining the relative amount of valuable matter in comminuted particles.

40 As shown in the figure, the apparatus comprises a receptacle A which tapers from its top downwardly, and which ends at its bottom in a tubular portion C of small diameter. Between the tapering portion A and the tubular portion C there is a glass-cock B. The tubular portion C is connected by a U-shaped portion F with a supply pipe E through which a suitable flushing liquid such as water is supplied to the bottom part of the receptacle A, the portions C, F and E being con-

nected with each other by rubber tubes H. The supply pipe E is connected either to the main or to a water tank disposed at a high level above the receptacle A, the supply of the water from the bottom of the said tank being preferred because thereby any access of air to the water and to the matter to be separated is prevented. The supply of water to the apparatus is controlled by means of a cock K. The top end of the receptacle A 55 is formed with a tubular stud L in which an overflow pipe D is fitted by means of a stopper I, the said overflow pipe having its end connected to a comparatively long rubber tube G. By providing the stopper I the 60 pipe D and the tube G may be readily removed from the receptacle A. In the example shown in the drawing all the parts except the rubber tubes H and G and the stopper I are made from glass, so that the separating 65 operation may be readily observed. The cross-sectional area of the bore b of the cock B is equal to the cross-sectional area of the tubular portion C, and the bore of the bottom end of the tapering receptacle A is 70 equal in area to the said bore b. The inner diameters of the glass-pipes D, E and F and the rubber tubes G and H are alike, and they are larger than the inner diameter of 75 the tubular portion C, the bore b and the bottom part of the receptacle A. When it is desired to use the apparatus the cocks K and B are opened and so much water is admitted to the apparatus that the water within the receptacle A rises substantially to the level 80 indicated by the line a, whereupon the cock K and the cock B are closed. By thus partly filling the receptacle A with water the air is from the beginning expelled from the supply pipe E, the collecting pipe F and the tubular portion C. Further, the apparatus cannot be obstructed when filling the material to be tested into the receptacle A.

85 About 250 grammes of the material to be tested, that is finely comminuted rock or earth, are stirred in water and filled into the receptacle A through the intake L thereof, whereupon the overflow pipe D is again fitted into the said intake.

90 Now simultaneously the water supply cock 100

K and the cock B of the receptacle A are opened, the pressure of the water being such that the material within the receptacle A is energetically flushed and stirred. Ordinarily 5 a pressure of $\frac{1}{3}$ atmosphere will be satisfactory. Thereby the time of the washing operation will be comparatively short. Before the receptacle A has been filled with water, and the finest particles or slime begin to 10 escape through the overflow pipe D, the pressure of the water is reduced by partly closing the cock K, so that the finest particles of the valuable ore or metal cannot be carried away together with the finest waste matter 15 or slime. The pressure needed in the said operations depends on the size of the grains of the material, and it must be the smaller the finer the said grain is.

After a few minutes the matter within the 20 receptacle A will be clear, so that only clear water flows through the overflow D. Now the first part of the operation is finished, and the separation of the particles of ore or metal begins.

25 For this purpose the flow of the water and the pressure thereof are reduced so far that the material within the receptacle A sinks to the lowermost point of the said receptacle, while it is just held floating within the said 30 receptacle above the bore b of the cock B by the continuously entering water.

Now the long rubber tube G is lifted above the top part of the whole apparatus. Thereby the head of water within the receptacle A 35 and therefore the resistance opposed to the flow of the water are increased, because the suction caused by the water flowing downwardly within the tube G is eliminated. By the reduction of the flow of the water the particles 40 before held by the flow of the water in the bottom part of the receptacle A and above the cock B are able to sink in opposition to the reduced flow of the water through the tubular portion C and into the collecting pipe 45 F, where they are deposited by reason of the comparatively large cross-section of the said collecting pipe. If now the rubber tube G is again lowered, the velocity of the water is again increased, and the lighter particles are 50 flushed from the pipe F upwardly and into the receptacle A, while the particles of higher specific gravity, such as gold, platinum and the like, remain on the bottom of the collecting pipe F.

55 Thus the separation of the particles of ore is effected while the water continues to flow through the apparatus, and it is deposited because the cross-sectional area of the collecting pipe F is larger than that of the tubular portion C, which results in a reduced 60 velocity of the water within the pipe F.

The upward and downward movement of the tube G may be repeated from 20 to 30 times, until a concentrated deposit is obtained 65 within the collecting pipe F, which deposit

may still contain particles of foreign matter. For removing the said foreign matter the flow of the water is slightly increased by further opening the cock K, and the rubber tube G is several times lifted and lowered, the said 70 lifting and lowering however amounting in this case only to a few centimeters. By the small variations of the head of the water and the velocity thereof a perfectly pure deposit is obtained in the pipe F. When this result 75 is obtained the cock K and the cock B are tightly closed.

Now the collecting pipe F may be removed from the apparatus by loosening the rubber tubes H. The concentrated matter is 80 poured into a cup, the water is decanted, and the concentrated matter is dried, whereupon it may be microscopically or chemically examined.

The separation of the matter may be repeated until no particles of ore or metal are deposited within the collecting pipe, that is until all the heavier minerals, particles of ore or the like have been separated from the raw material. Finally the receptacle A is emptied 90 through the cock B and the tubular portion C, whereupon the apparatus is ready for further use.

We wish it to be understood that we do not limit ourselves to the manner of producing 95 the variation of pressure within the receptacle by the method described herein, and that other means may be used for this purpose. For example the pipe G or the overflow D may be provided with a throttling member. 100 Further, a suction valve may be provided in the intake pipe E for periodically reducing the pressure of the water within the supply pipe E.

By our improved method and apparatus the 105 following advantages are obtained:

1. The flushing and separation of the material is carried out in a single apparatus in a continuous flow of water and while excluding the air, so that even particles of ore which may float on the surface of the water are not lost.

2. Separation is effected within a collecting pipe which may be readily closed and removed, and in which all the valuable matter 110 is deposited. If the raw material contains several minerals of different specific gravities the said minerals are separately collected.

3. The accuracy of the method is such that perfectly pure microscopic preparations or concentrated matter for chemical investigation are obtained. Therefore our improved system may be used not only for examining finely comminuted rock or earth, but it may also be used for examining strata. If noble metals are contained in the material to be investigated in a finely distributed and metallic state, even traces of the said metals may be detected. Therefore our improved system may be used for continuously testing

noble metal analyses, and it may be used in lieu thereof, because in case of material taken from the same deposit the amount of the matter deposited within the collecting pipe indicates the amount of noble metal contained in the ore. If the noble metal does not contain much ore, and it is found in a finely divided metallic state, it is possible after some experience to deliver exact estimates as to the actual 10 content in noble metal.

4. By reason of the uninterrupted flow of water which is alternately more or less energetic, the separation within the receptacle is continued during the whole duration of the 15 process, so that successively all the heavier particles of ore must pass into the collecting pipe by reason of the variations of the head of water, where they are precipitated. Therefore the new apparatus operates with 20 a high degree of uniformity.

5. An important advantage of the invention resides in the fact that the separation of the particles of ore and the like may be completed within a very short period of time. 25 After the flushing of the raw material has been finished which requires more or less time according to the amount of the material and the size of the grain, the separation of the particles of ore may be rapidly completed. 30 For example, if the material within the receptacle is 250 grammes, after 10 minutes about 50% of all the valuable ore may be deposited within the collecting pipe. If the amount is smaller, a much higher proportion 35 of the material is separated within the same time.

6. By constructing the whole apparatus from glass all the flushing and separating operations can be observed. The apparatus 40 may be readily taken into operation whenever it is needed, because only water is needed for carrying out the process.

We claim:

1. The herein described method of separating metal or ore from a mixture of metal or ore and comminuted matter of lower specific gravity, which consists in subjecting a quantity of the mixture to an upwardly directed current of a suitable liquid of such 45 velocity as to stir the said mixture while maintaining the same at a predetermined point, and thereafter partially reducing the quantitative flow of the liquid at said point sufficiently to permit the components of 50 higher specific gravity to sink within the current of liquid in opposition to the flow thereof.

2. The method described in claim 1, in which the quantitative flow of the liquid is several times and alternately reduced and increased to effect substantially complete separation.

3. The herein described method of separating comminuted substances of different

specific gravities which comprises subjecting a mixture of the substances to an upwardly directed current of liquid of such velocity as to to agitate and suspend the mixture at a predetermined region in the current of liquid while avoiding substantial flow of the components of the mixture either with or against the current of liquid and subsequently intermittently damming up the liquid outflow sufficiently to partially reduce the flow and effect relative settling of the components of higher specific gravity against the current to a region having a lesser flow rate than that at said first mentioned region.

4. The herein described method of separating comminuted substances of different specific gravities which comprises subjecting a mixture of the substances to an upwardly directed current of liquid in an upwardly expanding zone, adjusting the velocity of said current until the mixture is suspended above the constricted part of said zone and then intermittently and alternately reducing the flow of the liquid until the components of higher specific gravity settle through the 80 constricted part of said zone into a second enlarged zone and increasing the flow to carry any lighter components settling in said second zone back into said first zone.

5. An apparatus for separating metal or ore from comminuted matter of lower specific gravity, comprising a receptacle which is open at its top and bottom and which tapers from its top downwardly, means for closing said receptacle at its bottom, a horizontally extending stratifying receptacle communicating with and of larger cross-section than the bottom of said tapering receptacle, means for supplying a suitable liquid through said collecting receptacle in contact with material settled therein into said tapering receptacle, an overflow connected with the top part of 90 said tapering receptacle, and means for varying the flow of the liquid through said receptacles.

6. An apparatus for separating metal or ore from comminuted matter of lower specific gravity comprising a tapering receptacle having a restricted inlet at the bottom and an outlet at the top thereof, a flexible tube connected to said outlet, a U-shaped collecting receptacle communicating with the inlet of said tapering receptacle and of larger flow cross-section than said inlet and means for supplying liquid under a predetermined 100 steady hydrostatic head through said collecting receptacle to said tapering receptacle and contacting it with the material in said collecting receptacle.

In testimony whereof we hereunto affix 105 our signatures.
